CLAIM

The ornamental design for a lighting fixture, as shown and described.

DESCRIPTION

FIG. 1 is a perspective view of a lighting fixture of the claimed design;

FIG. 2 is a right end view and a left end view of the lighting fixture of FIG. 1;

FIG. 3 is top elevational view of the lighting fixture of FIG. 1 of the claimed design showing about one-half of the diffuser portion with roundels;

FIG. 4 is a front elevational view of the lighting fixture of FIG. 1 of the claimed design showing a full view of the diffuser portion;

FIG. 5 is a bottom elevational view of the lighting fixture of FIG. 1 of the claimed design showing about one-half of the diffuser without roundels;

FIG. 6 is a back elevational view of the lighting fixture of FIG. 1;

FIG. 7 is a perspective view of an alternate embodiment of a lighting fixture of the claimed design showing two rolled trim bars; and,

FIG. 8 is a perspective view of an alternate embodiment of a lighting fixture of the claimed design showing flat end portions.
